PAY-OFF REEL

George Wynn, Coraopolis, Pa., assignor to Jones & Laughlin Steel Corporation, Pittsburgh, Pa., a corporation of Pennsylvania.

Application April 30, 1953, Serial No. 352,200

4 Claims. (Cl. 242—84)

1

This invention relates to pay-off reels for feeding wire, rods, or like flexible material in coil form to processing apparatus. It is more particularly concerned with adjustable pay-off reels which can accommodate coils of wire or the like of several different internal diameters.

It is an object of my invention to provide a pay-off reel which may be quickly adjusted to receive and handle coils of different internal diameters.

It is another object of my invention to provide a double-deck pay-off reel which can be adjusted to accommodate coils of various internal diameters.

It is another object of my invention to provide a double-deck pay-off reel with improved means for transferring a coil from the upper to the lower deck. Other objects of my invention will appear in the course of the following description of my invention.

A present preferred embodiment of my invention is illustrated in the accompanying drawings in which:

Figure 1 is an elevation partly in section of a reel.

Figure 2 is a plan view of the reel of Figure 1.

Figure 3 is a plan view partly in cross section on the plane III—III of Figure 1.

Figure 4 is a detail view in cross section of a portion of my apparatus on the plane IV—IV of Figure 1.

Figure 5 is a detail view in cross section of another portion of my apparatus on the plane V—V of Figure 1.

Figure 6 is a detail view in cross section of another portion of my apparatus on the plane VI—VI of Figures 2 and 3.

The apparatus shown in the drawings includes a stationary mounting designated generally 3, a lower rotatable deck assembly designated generally 1 and an upper rotatable deck assembly designated generally 2. The stationary mounting 3 comprises a base plate 6 provided with a collar 7 in which is mounted an upright cylindrical shaft 8. A set screw 9 holds shaft 8 rigidly in collar 7.

Lower deck assembly 1 includes a base member 11 which may be circular in form and an upper cross member 12 which may take the form of a spider as shown. Base member 11 and upper member 12 are rigidly connected by pairs of upright members 13—13. Four such pairs are shown in the drawings, particularly Figure 3, uniformly disposed at angular intervals of 90° about the circumference of a central circular portion of the

2

base 11, but a greater or smaller number of such paired members 13 may be employed as desired. These members 13 define a framework over which a coil may be placed. A bearing 15 is fixed to the underside of base 11 and is disposed about upright shaft 8 so that lower deck assembly 1 may rotate about shaft 8 and have its weight carried by bearing 15. Bearing 15 may be a ball bearing as shown in the drawing. Cross member 12 has fixed to it by welding or other means a cylindrical sleeve 17 surrounding upright shaft 8, and this sleeve 17 is provided with a bushing 16 which may be brass or other bearing metal to provide an upper bearing for lower deck assembly 1.

Base member 11 of lower deck assembly 1 has welded thereto spacer strips 20 upon which the coil of rod or wire may rest. Between each pair of upright members 13—13, and adjacent spacer strip 20, is positioned a movable upright member 21. Each member 21 slides on base 11 between a pair of upright members 13—13 so that the coil centering framework formed by members 13 may be increased in diameter to center coils of greater internal diameters. Each movable upright member 21 is provided with holes 22, and one of each pair of members 13—13 is provided with pin means designated generally 24 which extend through member 13 and into a hole 22 of member 21, so locking member 21 in position with respect to member 13. Upright shaft 8 is provided with a collar 26 which is fixed to it by set screw 27 so that the lower face of collar 26 just clears the upright face of base member 11. This collar 26 holds lower deck assembly 1 in place on the stationary mounting 3, and prevents scale and dirt from getting into bearing 15.

Pin means 24 mentioned above are shown in more detail in Figure 6. A cylindrical casing member 30 is fixed to upright member 13 and is provided with a cap 31 having an aperture in its end through which passes a rod 32. The inner end of rod 32 carries a plug 33 dimensioned to fit in hole 22 previously mentioned, and provided with a shoulder 34 of greater diameter than hole 22. A coil spring 35 within sleeve 30 urges plug 33 outwardly. Plug 33 may be withdrawn from hole 22 by pulling on handle 36 of rod 32.

A bearing 40, which again may be a ball bearing as shown, is fitted to upright shaft 8 and rests on sleeve 17 of lower deck 1. A cylindrical sleeve 41 is rotatably mounted on upright shaft 8 and is supported by bearing 40 previously described. This sleeve 41 is provided with a projecting longitudinally extending key 42 as shown.

A collar 44 is fixed to sleeve 41 near its upper end and is provided with a projecting handle 45. This collar 44 supports a collar 47 which can rotate with respect to sleeve 41 and collar 44. Collar 47 is shown as formed with four forked or bifurcated projecting members 48. Each such member 48 is pivotally connected to a projecting arm 50 by a pin 51. These projecting arms 50 comprise an upper outwardly extending portion 52, an intermediate portion 53 more or less vertical, and a lower outwardly extending portion 54 upon which rests the coil of wire or rod carried by upper deck assembly 2.

A collar 56 is positioned about sleeve 41 at the bottom thereof and is rotatable with respect thereto. This collar 56 rests upon bearing 40 previously mentioned. Above this collar 56 is positioned a collar 57 which is identical in construction with collar 47 previously described except that collar 57 is formed with a keyway 58 at one portion of its internal circumference. This keyway 58 is dimensioned to pass key 42 carried by sleeve 41 when key 42 and keyway 58 are aligned. Collar 57 can rotate with respect to sleeve 41 if key 42 carried by sleeve 41 is not aligned with keyway 58 of collar 57. When key 42 is aligned with keyway 58, collar 57 can slide upwardly along sleeve 41 and in this position cannot rotate with respect to sleeve 41. Collar 57 is shown as formed with four forked or bifurcated projecting members 60. Each of these projecting members 60 is pivotally connected by a pin 62 to a strut assembly designated generally as 61. The strut assembly 61 is composed of an inner link 64, and an outer link 65. The outer end of link 65, which may be forked, is pivotally connected to arm 50 by a pin 66. The inner end of link 65 is provided with a longitudinal recess into which the outer end of link 65 may enter or telescope so that the overall length of strut assembly 61 may be varied by varying that portion of link 64 which is telescoped within link 65. The recess of link 65 is dimensioned so that link 64 can move longitudinally only. Pin means 67, which may be similar to pin means 24 previously described, are affixed to link 65, and link 64 is provided with a number of holes 68 which may be engaged by pin means 67 so as to lock link 64 to link 65 in any one of several selected positions.

Upper deck assembly 2 is held on vertical shaft 8 by top plate 70 attached by screw 71.

The operation of my pay-off reel will now be described, with reference to the embodiment described above and illustrated in the accompanying drawings. A coil of wire, rods, or other flexible material may be loaded from above onto upper deck assembly 2 of my apparatus in the same manner that a coil is loaded onto a conventional pay-off reel. The upper deck assembly 2 is first adjusted to accommodate a coil of the desired internal diameter by adjusting the overall length of strut assembly 61 as has been described. The length of each strut assembly 61 controls the distance that each arm 50 projects outwardly, and so controls the diameter of the coil supporting framework formed by arms 50. Each strut assembly 61 must, of course, be adjusted to the same length. The adjusted strut assemblies are locked in position by pin means 67 described previously. When a coil of wire or rods is in position upon upper deck assembly 2, it is supported by the outwardly extending portion 54 of each arm 50, and the wire or rods may be payed off from the coil so supported, since up-

per deck assembly 2 rotates freely on bearing 40 previously described.

Lower deck assembly 1 may be likewise adjusted to accommodate a coil of the desired internal diameter by moving movable upright members 21 outwardly with respect to fixed upright members 13 as has been previously described, and such movable members 21 may be locked into one of several positions by pin means 24 as has been previously described.

The weight of a coil carried by outwardly extending portions 54 of arms 50 exerts a force on each arm 50 tending to move it downwardly and inwardly about pin 51 connecting it with collar 47. The struts 61 transmit such force to the upright shaft 8 through collar 51. The horizontal components of the forces transmitted to this collar by the arms 50 balance, of course, leaving a vertical component which urges collar 57 upwardly. Key 42, however, normally prevents collar 57 from sliding upwardly over sleeve 41 and since sleeve 41 rotates freely about shaft 8 on bearing 40 the whole upper deck assembly 2 normally rotates with sleeve 41.

A coil of wire or rods is transferred from upper deck assembly 2 to lower deck assembly 1 by rotating sleeve 41 with respect to collar 57 until key 42 of sleeve 41 is aligned with keyway 58 of collar 57. The rotation of sleeve 41 is conveniently accomplished by exerting a force on projecting handle 45. When this key and keyway are aligned, the vertical component of force previously mentioned causes collar 57 to slide upwardly over sleeve 41, and this movement in turn causes each strut 61 to pivot upwardly in a vertical plane about its connecting pin 66. The horizontal distance between pins 66 and 62 is thus shortened and arms 50 therefore pivot downwardly and inwardly about pins 51. My upper deck assembly 2 is so dimensioned that when collar 57 is adjacent sleeve 44 the outer tips of outwardly projecting ends 54 are retracted within the internal diameter of the coil for which my reel is adjusted. The unsupported coil is thus permitted to drop onto lower deck assembly 1 where it is supported by spacer elements 20. A coil so positioned on lower deck assembly 1 may be payed off freely since this lower deck assembly rotates freely about shaft 8 independently of upper deck assembly 2 as has been described.

It will be appreciated that upper deck assembly 2 may be independently employed in another way as an adjustable pay-off reel for wire or rod coils. If this apparatus is so dimensioned that the arms 50 accommodate a coil of a given maximum internal diameter when collar 57 is held in its lower position and accommodate a coil of a given minimum internal diameter when collar 57 is in its upper position, the reel can be changed from one diameter of coil to the other merely by rotating sleeve 41 with respect to collar 57 as has been previously described.

It will also be appreciated that my pay-off reel can be used to pay off two coils of wire independently but simultaneously to two different processing apparatuses if desired.

Although the embodiment of my invention herein described and illustrated may be adjusted to accommodate coils of three different internal diameters, those skilled in the art will understand that my invention may be made adjustable to a greater or smaller number of coil sizes. One embodiment of my invention has been constructed to accommodate coils of 23, 27, and 31

inches internal diameters. This reel will handle 600 pound coils of wire rods.

I claim:

1. A pay-off reel for coils of flexible material comprising stationary supporting means, a collar rotatably mounted on the supporting means at the upper end thereof, a plurality of arms pivotally connected to the collar and extending outwardly, then downwardly, and then outwardly, struts pivotally connected to the arms bracing them against the supporting means to form a framework over which a coil may be placed and by which such coil may be carried for paying off, and means for adjusting the length of these struts so as to adapt the reel to coils of different internal diameters.

2. A pay-off reel for coils of flexible material comprising stationary supporting means, a sleeve rotatably mounted on the supporting means, a first collar rotatably mounted on the sleeve at the upper end thereof, a plurality of arms pivotally connected to the first collar and extending outwardly, then downwardly, and then outwardly, struts pivotally connected to the arms adjacent their outwardly extending lower portions and to a second collar rotatably mounted on the sleeve in spaced relation with the first collar and slidably over the sleeve, a key elongated parallel to the sleeve and projecting therefrom, a mating keyway in the second collar, and means for causing relative rotary movement between the sleeve and the second collar whereby the key and keyway are brought into alignment and the second collar permitted to slide along the sleeve causing the arms to move downwardly and inwardly about their pivotal connections with the first collar.

3. A pay-off reel as in claim 2 in which the top of the sleeve adjoins the top of the stationary supporting means, the second collar slides upwardly along the sleeve when key and keyway are in alignment, and the means for causing relative rotary movement between the sleeve and the second collar comprise a handle projecting out-

wardly from the sleeve adjacent the upper end thereof.

4. A pay-off reel for coils of flexible material comprising stationary supporting means, a lower deck assembly rotatably mounted on the supporting means comprising a base member, a plurality of fixed uprights disposed about the circumference of a central area of the base member, a cross member joining the upper ends of the fixed uprights, a plurality of radial movable upright plates each positioned adjacent a fixed upright and means for adjustably positioning the movable upright plates radially outwardly of the fixed uprights so as to adapt the lower deck assembly to coils of different internal diameters, and an upper deck assembly comprising a collar rotatably mounted on the supporting means at the upper end thereof, a plurality of arms pivotally connected to the collar and extending outwardly, then downwardly, and then outwardly, struts pivotally connected to the arms bracing them against the supporting means to form a framework over which a coil may be placed and by which such coil may be carried for paying off, means for adjusting the length of the struts so as to adapt the upper deck assembly to coils of different internal diameters, and means for moving these struts about their pivotal connections to cause the arms to move downwardly and inwardly about their pivotal connections with the collar and drop the coil onto the lower deck assembly.
